AIR CLEANER

Frank A. Donaldson, Minneapolis, Minn.

Application April 13, 1935, Serial No. 16,196

9 Claims. (Cl. 183—15)

My present invention relates to air cleaners and has for its object to improve the same in various important particulars, whereby the efficiency of the same is increased and the manufacture 5 thereof facilitated, and especially the invention is adapted for use in connection with internal combustion engines. The improved air cleaner is of very compact formation, has no parts to get out of order or require frequent cleaning, and in 10 actual use has been found highly efficient as used in connection with internal combustion engines designed to run at very high as well as low speeds.

A commercial form of the improved air cleaner 15 is illustrated in the accompanying drawing, wherein like characters indicate like parts throughout the several views.

Referring to the drawing:

Fig. 1 is a view partly in elevation but chiefly 20 in vertical section showing the improved air cleaner;

Fig. 2 is a fragmentary plan view of the air 25 cleaner, some parts being broken away;

Fig. 3 is a fragmentary section taken on the 30 line 3—3 of Fig. 2; and

Fig. 4 is a horizontal section taken on the line 35 4—4 of Fig. 1, some parts being broken away.

Carburetors used in connection with internal 40 combustion engines, such, for example, as the Ford automobile engine, have air intake tubes to which the air cleaners are adapted to be attached. For attachment to such carburetor intake tubes, the present air cleaner is provided with an axial clean air delivery tube 5, which, as 45 shown, is provided at a point considerably above its lower end, with a secured inner flange 6 that holds a pliable gasket 7 adapted to rest upon the intake tube of the carburetor, when the latter is telescoped into the lower end of said tube 5. An annular plate 8 is secured to the lower portion 50 of the tube 5 at a point above the lower end thereof and is provided with an upstanding flange or inverted skirt 9. This bottom plate and flange, as will presently appear, afford an oil well, and the top of the air cleaner is closed by a hood-forming plate 10 that is rigidly but detachably 55 secured, by a nut-equipped stud 11, to a cross-bar 12, which, in turn, is rigidly secured within and extends diametrically of the upper portion of the tube 5.

Preferably and as shown, the under surface of the plate 10 is provided with a silencing lining 13 held in place by a woven wire frame 14. An approximately cylindrical inner skirt 15 is secured at 16 to the outer portion of the hood.

10 and depends within the outer skirt or flange 9 from which it is inwardly spaced, so as to leave an annular air intake passage 17 that leads downwardly to the outer portion of the oil well 18 formed by the bottom plate 8.

An annular baffle plate 19 having large air 15 passages 20, is secured to the upper portion of the air tube 6 and its outer edge is secured to the upper edge of the inner skirt 15 and to the hood-forming plate 10.

As an important feature, the upper edge of the skirt 15 and the outer edge of the plate 19 have outturned marginal flanges that are interlocked to the plate 10 by a clinch joint formed at 16 by rolling the immediately adjacent portion of the 20 plate 10 around and in air-tight engagement with the said out-turned flanges of said elements 15 and 19. This rolled clinching rib is thus made approximately U shaped in radial section and it is preferably formed at a considerable distance 25 inward from the extreme outer edge of said plate 10, so as to form an eave 21 that overlies the annular air intake channel 17, and preferably extends slightly inward of the inverted outer skirt 9. The extreme upper edge of said inverted skirt 25 9 is bent inwardly at 22 for a purpose which will presently appear. Inasmuch as the plate, together with the parts attached thereto, is detachable from the clean air tube 5, the plate 19 is made detachable from said tube 5; and this 30 as shown, is accomplished by providing said plate 19 at its inner edge with a downturned cylindrical hub flange 19a that preferably is of the same diameter as the tube 5 so that it aligns therewith. As a further feature, a sleeve 23 is telescoped 35 onto the tube 5 and the hub flange 19a is telescoped into the extreme upper end of said sleeve 23. As a further important feature, the sleeve 23 is provided near its upper portion below the hub flange 19a with circumferentially spaced perforations 23a, the important purpose of which 40 will appear in the description of the operation. The annular space between the sleeve 23 and the inner skirt 15 is filled in with an oil and dust-intercepting screen 24, which may take various 45 forms, but will preferably be of a character disclosed and claimed in an application of William H. Schulz, entitled "Air cleaner screen and method of producing the same", S. N. 725,515, filed May 14, 1934.

To further hold this annular screen filler in position in respect to the removable part of the air cleaner, the lower end of the sleeve 23 is shown as provided with an outwardly projecting flange 23b, and the lower edge of the inner skirt 55

15 is provided with an inwardly projecting annular flange 16a. With this structure, when the hood or plate 10 is detached and removed, the sleeve 23, skirt 15 and screen 9 will be removed therewith and, of course, the said elements will be simultaneously replaced.

In the air cleaner illustrated, the bottom plate 8 is shown as provided with an upstanding annular cup-forming flange 24 with circumferentially spaced perforations or oil passages 25; but the structure involving this cup-forming element and the well formation are not herein claimed, since the same are the subject matter of an application filed of even date herewith 15 by Wilfred W. Lowther, entitled "Air cleaner."

Operation

Under the suction produced by the engine to which the cleaner is applied, vacuum or suction 20 will be produced in the axial air delivery tube 5 and this will cause a flow of air to the air cleaner, first downward through the annular air intake passage 17, thence to the outer portion of the oil well, and from thence over the upper 25 edge of the cup-forming flange 24 up through the oil and dust-intercepting screens and thence to the engine through the delivery tube 5. The air thus delivered against the surface of the oil in the outer portion of the well, will violently 30 agitate the oil and will dash the same into a spray or foam that will carry the oil upward into the screens.

The dust-laden air carried into the screens will be carried upward therethrough to an extent depending on the degree of suction, but 35 will not be carried completely through the same. In fact, the oil under any normal operation, will not be carried to an altitude above the air ports or perforations 23a of the sleeve 23. As the air 40 releases the oil, it will run back through the screens chiefly into the cup formed on the bottom plate by the flange 24. Also, with the cup formation, the oil overflowing the upper edge of the flange 24 and running out through the oil 45 ports or passages 25, will deliver directly into the incoming dust-laden air so that there will be a continuous tendency of the oil to flow outward to meet the incoming air; but as above indicated, this cup feature action is not herein 50 claimed per se. Of course, the oil that is delivered to the screen will flow over the screen surfaces and will intercept the dust-laden oil and will be, by the latter, carried back to the oil well, while the clean air will be delivered 55 through the air ports 20, under the hood 10 and through the clean air delivery tube 5 to the carburetor. When the engine is idle, the oil will settle back into the oil well to a normal altitude 60 which will usually be approximately the lower portions of the screens or the upper edge of the flange 24, when said flange is employed.

The tube 5 is not telescoped around the sleeve 23 in such tight fit as to absolutely prevent the passage of air between the two.

In practice, it is not feasible to make an air-tight joint between the sleeve 23 and tube 5, and hence in practice it has been found that the vacuum produced in the tube 5 and hence through the screens and the air intake passage 70 will cause some flow of oil between said sleeve 23 and tube 5 with the result that some oil will be delivered to the carburetor, which, for obvious reasons, is a feature not desired. I have found that by placing the air ports 23a in the upper portion of the sleeve 23 near the top 75

thereof, but below the joint between the upper edge of the tube 5 and the hub flange 10a, the vacuum or suction between the said elements 23 and 5 will be broken and no oil will be delivered to the carburetor by passage between 5 the sleeve 23 and tube 5, even when there is a considerable clearance or looseness of fit between said elements 23 and 5.

By the use of the clinched joint 16 between the elements 10, 15 and 19, the said three elements are very firmly united and, in practice, I have found that this may be accomplished by a properly designed rolling mechanism at a very small cost. Moreover, this kind of joint is capable of being produced at a place considerably inward from the extreme outer edge of the hood-forming plate, thereby providing a projecting 15 20 25 30 35 40 45 50 outer edge rigidly secured to said hood and to the upper edge of said inner skirt.

3. The structure defined in claim 1 in which said hood-forming plate, inward of its outer edge, 5 is formed with an integral annular crimp that embraces and rigidly engages the upper edge of said inner skirt and supports the latter.

4. The structure defined in claim 2 in which said hood-forming plate, inward of its outer edge, 10 is formed with an integral annular crimp that embraces and rigidly engages the upper edge of said inner skirt and the outer edge of said baffle plate and supports said inner skirt.

5. An air cleaner comprising an axial air delivery tube, an oil-well-forming bottom plate extended outward from the lower portion of said axial tube and provided at its rim with an inverted outer skirt, an inner skirt spaced from said outer skirt and bottom plate to form a 15 downwardly leading annular air intake passage, an air pervious dust and oil-intercepting means in the space between said axial tube and inner skirt, and a hood-forming plate supported above said intercepting means and the upper end of said axial tube and rigidly secured to the upper edge of 20 said inner skirt, the upper edge of said outer skirt being inwardly turned to form a downwardly deflecting oil stop.

6. An air cleaner comprising an axial air delivery tube, an oil-well-forming bottom plate extended outward from the lower portion of said axial tube and provided at its rim with an inverted outer skirt, an inner skirt spaced from said outer skirt and bottom plate to form a 25 downwardly leading annular air intake passage, an air pervious dust and oil-intercepting means in the space between said axial tube and inner skirt, a hood-forming plate supported above said intercepting means and the upper end of said

axial tube and rigidly secured to the upper edge of said inner skirt, and a sleeve telescoped around said axial air delivery tube and perforated in its upper portion for the purpose stated.

7. An air cleaner comprising an axial air delivery tube, an oil-well-forming bottom plate extended outward from the lower portion of said axial tube and provided at its rim with an inverted outer skirt, an inner skirt spaced from said outer skirt and bottom plate to form a downwardly leading annular air intake passage, an air pervious dust and oil-intercepting means in the space between said axial tube and inner skirt, a hood-forming plate supported above said intercepting means and the upper end of said axial 15 tube and rigidly secured to the upper edge of said inner skirt, a perforated baffle plate applied to the upper end of said axial tube and having its outer edge rigidly secured to said hood and to the upper edge of said inner skirt, and a sleeve 20 telescoped around said axial air tube, said intercepting means being secured between said sleeve and inner skirt and being removable with said sleeve, inner skirt and hood plate.

8. An air cleaner comprising a casing having 25 concentric walls forming an axial air passage and an outwardly spaced annular air passage, an air pervious dust and oil-intercepting means in the space between said axial air tube and surrounding annular air passage, said axial and annular air passages being connected for the passage of air through said intercepting means, and, a sleeve telescoped around said axial air tube in loose frictional contact therewith and perforated in its upper portion for the purpose stated. 30 35

9. The structure defined in claim 8 in which said sleeve is interposed between said axial air tube and the dust and oil intercepting means.

FRANK A. DONALDSON.
